(57) **CLAIM**

The ornamental design for a personal computer, as shown and described.

DESCRIPTION

FIG. 1 is a perspective view of front, top and right side of a personal computer showing our new design;

FIG. 2 is a perspective view of rear, top and left side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing an intermediate state that a stand is open;

FIG. 10 is a rear perspective view showing an intermediate state that a stand is open;

FIG. 11 is a right side view showing an intermediate state that a stand is open;

FIG. 12 is a perspective view showing a final state that a stand is open;

FIG. 13 is a rear perspective view showing a final state that a stand is open;

FIG. 14 is a rear view showing a final state that a stand is open;

FIG. 15 is a right side view showing a final state that a stand is open;

FIG. 16 is a top view showing a final state that a stand is open; and,

FIG. 17 is a bottom view showing a final state that a stand is open.

1 Claim, 14 Drawing Sheets
